APPARATUS FOR HEATING OIL

Filed Feb. 16, 1926

John A. Ferkes,
BY *Blakelock, Bratt & Ferkes*,
ATTORNEYS.

UNITED STATES PATENT OFFICE.

JOHN A. YERKES, OF LONG BEACH, CALIFORNIA.

APPARATUS FOR HEATING OIL.

Application filed February 16, 1926. Serial No. 88,689.

This invention relates to heating apparatus, and more particularly to an apparatus for heating the oil in oil wells to reduce the viscosity of the oil, so that it may be more easily 5 and efficiently pumped out of the well and in greater volume than otherwise.

One of the objects of the invention is to provide an oil well heating apparatus of the character stated, whereby the entire oil 10 formation of the well may be heated.

Another object is to provide an oil well heating apparatus by means of which the oil will be heated below the pump and all the way up the pump and pump tubing to the top 15 of the wall, so that the oil will be more effectively heated and its viscosity reduced to a minimum, in order that the pump may operate more efficiently and pump the oil out of the well in greater volume than is possible 20 with other pumping apparatus.

Another object is to provide an oil well pump and an oil heating apparatus combined in one structure so that the same may be raised or lowered in the oil well as a unit.

25 A further object is to provide a continuous circulating heating system for heating the oil in oil wells.

With the above and other objects in view, the invention consists in the novel and useful 30 provision, formation, construction and interrelation of parts, members and features, all as shown in the drawing, hereinafter described, and finally pointed out in claims.

In the drawing:

35 Figure 1 is a view partly in elevation and partly in vertical section of my heating apparatus as applied to an oil well and pump;

Figure 2 is a vertical section on an enlarged scale of the lower portion of my heating 40 apparatus as shown in Fig. 1;

Figure 3 is a vertical section of the lower portion of a modified form of my invention;

45 Figure 4 is an enlarged side view of a portion of my invention showing the holding means for the water circulating pipe; and,

Figure 5 is a plan view of Fig. 4.

Corresponding parts in all the figures are designated by the same reference characters.

Referring with particularity to the drawing, I have shown an oil well W lined with a casing C and an upper casing section C' in which the upper portion of the casing C telescopes, there being perforations c in the lower portion of the casing C and a head c' detachably fitted on the upper end of the casing section C'.

The head c' is provided with a central threaded opening c² in which is screwthreaded the upper portion of a pump water jacket tube J which extends downwardly into the 60 casing C, the lower end of said tube being screw seated in the upper end of a screw coupling K as at j, which coupling is screw-connected to the upper end of a perforated inlet tube I provided with perforations i. The 65 lower end of said inlet tube is coupled to the upper end of a hot water heating chamber H by means of a screw coupling L, which chamber rests in the bottom of the well, there being a head h gripped between the adjoining ends 70 of the inlet tubing I and the chamber H, which head separates the tube from the chamber. On the lower end of the chamber H is connected a cap h' by means of a screw coupling h². The water jacket tube J includes 75 an upper section j' which is screw seated at its lower end in the opening c² of the head c' and is closed at its upper end by a head j².

A pump P extends through the water jacket tube J. This pump may be of the California 80 oil well pump type, but its shoe S, which is screw-seated on the lower end of its barrel 1, is formed with a conical end s which seats on a conical seat k in the upper end of the coupling K. The upper end of the pump 85 tube 2, which is coupled at its lower end to the upper end of the pump barrel 1 by coupling 3, extends through the head j² and a stuffing box j³ in said head. In the pump barrel 1 are the usual standing valve 4, 90 plunger 5. Garbutt rod 6 and nut 7 connecting said valve and plunger, and working valve 8 connected to the upper end of said plunger, to which latter valve is connected the lower end of the sucker rod 10 which extends through the stuffing box 11 in the upper 95 end of the pump tube 2, there being outlet pipes 12 and 13 leading from the upper end of the pump tube.

An apparatus for practicing my invention 100 includes a steam pump M, a water heating tank T, heating chamber H, and water jacket tube J. A steam supply pipe 15 leads into the steam operating cylinder m of the pump M and a steam exhaust pipe 16 leads 105 from said cylinder into the upper part of the water heating tank T where it is wound into a heating coil N and its outlet end n extended out of the lower part of the tank. The tank T is filled with water and a water pipe 17 leads 110 therefrom into the water cylinder m' of the pump M. A hot water inlet pipe 18 leads

from the cylinder m' through the well casting head c' , casing section C' , and casing C , into the lower end of the inlet tube I , through the head h into the heating chamber H to a point near the bottom thereof. The pipe 18 is split at 19 and its adjoining ends screw seated in a screw coupling 20 welded on the upper side of the head h . On the lower end of the pipe 18 in the chamber H is coupled 10 a perforated outlet cage 21. The pipe 18 is clamped on the water jacket tube J by band clamps 22 which engage the tube just above the joint couplings j^4 thereof. A by-pass 24 leads from the upper end of the heating 15 chamber H into the lower end of the hot water jacket tube J . An outlet pipe 25 leads from the upper end of the water jacket J into the top of the water heating tank T . In the modified form of my invention shown in Fig. 20 3 the pipe 18 leads into chamber H through the side thereof as at 30.

In operation the oil is pumped out of the well by the pump P through the inlet tube I , coupling K , shoe S , pump barrel 1 and pump tube 2. The water in the tank T is heated by the exhaust steam of the pump M passing through the coil N . Hot water is pumped by pump M out of said tank through pipe 17 into cylinder m' and from said cylinder 25 through pipe 18 and cage 21 into the heating chamber H , which heats the oil in the well below the pump P , and from said heating chamber the hot water is conducted through by-pass 24, water jacket tube J and outlet pipe 25 back into the tank T , the water passing 30 through the water jacket tube heating the oil in the pump P and in the pump tubing 2 all the way to the top thereof. The heating of the oil in the well below the pump by the hot 35 water in the chamber H and the heating of the oil in the pump and pump tube all the way to the top thereof by the hot water in the jacket tube J reduces the viscosity of the oil, so that the oil may be pumped more freely and 40 in greater volume from the well than otherwise.

The pump and heating apparatus including the pipe 18, chamber H , by-pass 24, and water jacket J , being combined in one structure, 45 may be raised or lowered in the well as a unit.

Having thus disclosed my invention, I claim and desire to secure by Letters Patent:

1. In combination with an oil well and pump, a hot water chamber below the pump, 55 a hot water jacket surrounding the pump, and means for circulating hot water through said chamber and jacket.

2. In combination with an oil well pump, and pump tube, a hot water chamber below said pump, a hot water jacket surrounding the pump and the pump tube, and means for circulating hot water through said hot water chamber and jacket. 60

3. In combination with an oil well and pump, a hot water chamber below the pump, 65 a hot water tank, a steam-operated pump, the exhaust pipe of said steam-operated pump leading into said hot water tank and formed in a coil therein, a hot water pipe leading from said tank into the pumping cylinder of 70 said steam-operated pump, a hot water pipe leading from said pump cylinder into said hot water chamber, and means for conveying the hot water from said chamber back to said hot water tank. 75

4. In combination with an oil well and pump, a hot water chamber below the pump, a hot water jacket surrounding the pump, a hot water tank, a steam-operated pump, the exhaust pipe of said steam-operated pump 80 leading into said tank and formed in a coil therein, a hot water pipe leading from said tank into the pumping cylinder of said steam-operated pump, a hot water pipe leading from 85 said pumping cylinder into said hot water chamber, a by-pass connecting said hot water chamber and said hot water jacket, and an exhaust water pipe leading from said jacket back into said tank.

5. In combination with an oil well pump 90 including a conical shoe and an inlet tube, a heating apparatus comprising a hot water jacket surrounding said pump, a coupling connecting said jacket and inlet tube, said coupling being formed with a conical seat 95 therein on which seats said shoe, a hot water chamber coupled on the lower end of said inlet tube, and means for circulating hot water through said chamber and said jacket.

6. In combination with an oil well pump 100 including a conical shoe and an inlet tube, a heating apparatus comprising a hot water jacket surrounding said pump, a coupling connecting said jacket and inlet tube, said 105 coupling being formed with a conical seat therein on which seats said shoe, a hot water chamber coupled on the lower end of said inlet tube, and means carried on the apparatus for circulating hot water through said hot water jacket. 110

In testimony whereof, I have signed my name to this specification.

JOHN A. YERKES.
